UNITED STATES PATENT OFFICE.

JOSEF KONRAD, OF SPOKANE, WASHINGTON.

MARINE LIFE-SAVING APPARATUS.

1,183,078.

Specification of Letters Patent.

Patented May 16, 1916.

Application filed April 5, 1915. Serial No. 19,271.

To all whom it may concern:

Be it known that I, JOSEF KONRAD, a citizen of the United States, residing at Spokane, in the county of Spokane and State of Washington, have invented certain new and useful Improvements in Marine Life-Saving Apparatus, of which the following is a specification.

This invention relates to improvements in marine life saving apparatus and it is one of the special objects of this invention to provide a life saving apparatus whereby one or more of the passengers or occupants of a sunken ship may be bodily elevated therefrom to the surface of the water and thereafter taken on board of a rescuing vessel.

A further novel feature consists in providing a ship with a habitable air tight housing into which the occupants of a sinking ship may enter and be preserved in safety notwithstanding the fact that the ship may be sinking beneath the surface of the water.

A further object of the invention is to equip the ship with an air supplying buoy which is mounted in such a manner that it will be free to float upon the water surface as the injured ship descends therebelow and which will function as an air supplying intake to the injured and sinking ship.

A further object of the invention is to connect the air supplying buoy with the air tight housing by means of a hollow cable or hose like conduit adapted to convey air from the buoy to the housing, and in this connection, it is a feature of the invention to provide operative means in the air tight housing for positively drawing a required supply of air downwardly thereinto.

My invention also includes a rescue container into which one or more of the ship wreck victims may enter to be bodily conveyed to the surface of the water, and in this connection, it is a feature of my invention to connect the container with the housing by a rescue line and windlass or like means whereby the container may not only be permitted to rise from the housing to the water surface but whereby it may also be withdrawn from the water surface down and into said housing.

It is also a feature of the invention to connect the buoy with the rescue container by means of a captive or guiding line or cable which is adapted to be carried by the buoy into an accessible position with respect to the

surface of the water so that a grapple hook mechanism may be slid down such captive line and into connection with the container so as to permit the latter to be positively hoisted to the surface by a rescuing vessel. 60

My improved buoy is also equipped with signals and communicating devices which are connected through the hollow air supplying conduit or hose with the interior of the air tight housing in such a manner as to permit the occupants of the latter to operate and utilize and otherwise transmit communication through said signal devices to the rescuing party.

My invention includes many other objects and features of construction which will be more fully described in connection with the accompanying drawings and which will be more particularly pointed out in and by the appended claims. 70

In the drawings: Figure 1 is a view in elevation showing a sunken ship equipped with the device of my invention and illustrating the manner in which a rescuing vessel utilizes such device to rescue the shipwrecked victims, Fig. 2 is a longitudinal vertical sectional view of the air tight housing with which a ship or vessel is to be equipped, Fig. 3 is a sectional view on line 3-3 of Fig. 2, Fig. 4 is a sectional view on line 4-4 of Fig. 2, Fig. 5 is a vertical sectional view of my improved buoy, Fig. 6 is an enlarged sectional view of the upper portion of my improved rescue container showing the manner in which the grapple hook is connected therewith to hoist the container by the hoisting cable to the rescuing vessel, Fig. 7 is an enlarged vertical sectional view of a portion of a partition and an improved manhole by means of which the air tight housing is divided off into a rescue container compartment and by means of which door access is possible from said compartment to the interior of said housing and vice versa. 75 80 85 90 95

Like characters of reference designate similar parts throughout the different figures of the drawings.

As illustrated, 1 designates a sunken ship resting at the bottom of a body of water. 2.

3 designates the water surface upon which a rescuing vessel 4 is floating in superposed relation with the sunken ship.

Upon a suitable deck 5, of a ship is mounted in securely anchored relation my improved air and water tight habitable hous- 110

- ing 6 which may be constructed of any desired material such as will be impermeable to air or water both as regards its texture and its joints and fittings. The housing 6 is divided by a partition 7 into a main safety chamber or compartment 8, of relatively large size, and a container compartment 9, of relatively small size. The partition 7, as will be seen more particularly by reference to Fig. 10 7, is provided with a manhole 10 which is adapted to be closed by a manhole cover or closure 11. Said closure is hinged at 12 to swing upwardly and to open into the main or safety compartment 8 and a suitable gas-15 ket 13 affords an air tight juncture between the closure and the partition 7 when the former is in a closed position. A bolt 14 is pivoted at 15, to the partition 7, and normally extends through a forked projection 20 16. A hand wheel 17, threaded onto said bolt 14 is provided for imparting a pressure to the cover 11 so that the latter may be closed with an air tight fit.
- An air pump 18, preferably of the reversible type is provided with a discharge opening 19 which opens into the safety compartment 8. Said pump is provided with a normally acting intake connection 20, connected by a pipe 21 which extends through a suitable packing 22 through the upper wall of the housing 6 to a hose or like tubular conduit 23 initially trained about a drum 24, mounted upon the housing 8. The drum 24 projects upwardly vertically from the top 30 wall of the housing 8 so that the conduit 23 is free to unwind from said drum. End 25 of said conduit is connected with pipe 21 and the remaining end 26 is connected with a coupling 27 which latter is attached in a bore 28 of my improved buoy 29. The main or lower body portion 29 of my improved buoy is preferably formed of wood or like initially buoyant material and the bore 28 preferably extends throughout the solid 40 body portion of the buoy. The remaining or upper portion 30, is hollow and converges from the maximum diameter at 31 about which an annular air tight shell 32 is disposed to add additional buoyancy. The upper end of the buoy is flared bell shaped as indicated at 33 and is provided with a diaphragm 34 having openings 35 therein for intake of air into the buoy.
- My improved buoy is provided with signal and communicating devices and I have shown a signal device of the visual type which may be in the form of an incandescent lamp 36, mounted upon said diaphragm 34 in such a manner as to shed its rays in an attracting manner about the top of the buoy. A cable 37 leads from said signal lamp through the hose or like conduit 26 and comprises conductors 38 and 39 which are shown diagrammatically leading from 50 said pipe 21 into the interior of said hous- ing 6. A similar lamp signal 40 is interposed in conductor 38 to light the interior of compartment 8 and show completion of circuit. Conductor 38 leads to a terminal 41 of a switch mounted upon switch board 42. A conductor 43 leads from the other terminal 44 of said switch to one pole of a source of current 45, the other pole of said source of current being connected to conductor 39.
- The buoy is provided with a door 46 for access into the upper hollow portion thereof and in such portion I mount a telephone instrument 47 which is connected by conductors carried in a cable 48 through bore 28 and conduit 23 into pipe 21. The telephone conductors, which are shown at 49 and 50, lead from said pipe 21 to a telephone instrument 52, mounted in compartment 8. Conductors 53 and 54 lead from said instrument 52 to a source of current 55. Thus it will be seen that after the buoy has been located by the rescuing vessel, a member of the rescuing party can enter the buoy and establish communication with the occupants of safety chamber 8.
- An electric motor 56 is shown connected with the pump 18 by a belt transmission 57 so that when it is necessary to provide a supply of air to safety chamber 8, such supply will be available through pipe 21, conduit 23 and buoy 29. An electric conductor 58 leads from said motor to one pole of a source of current 59 and the other pole of said source of current is connected with a conductor 60 to the poles 61 of a two point switch, mounted upon switch board 42. Conductors 62 and 63 lead from said switch to the motor. If desired, a one point switch may be utilized so as to eliminate conductor 63.
- The top wall of the housing 6 is provided with a buoy support 64 which serves to hold the buoy in an upright position and in such a manner as to freely release the buoy when the ship sinks.
- The upper portion of compartment 9 is open, as indicated at 65 and is shaped to closely conform to the external dimension of rescue container 66, the latter being shown 110 cylindrical in form. A guide 67 may coact with openings 65 to hold the container in a rigid position in the compartment 9. Said container 66 is provided with a flange 68 which coacts with the top of said compartment to limit descent of the container thereto, thereby insuring the projection of a portion of the container upwardly from the exterior of the housing 6. A suitable gasket 69 provides for a hermetical closure of compartment 9 when the container 66 is disposed in the compartment 9. The upper end of the container 66 is provided with a grapple connecting portion 70 which may be of an inverted bell shape form, the flange 71 serv- 120 125 130 135 140 145 150 155 160

ing for direct engagement of the hooks of a grapple. In the interior of the grapple head or connecting portion 70 is connected at 72 the lower end of a guiding or captive line or cable 73. Said captive cable 73 is trained about a vertically disposed drum 74 and its remaining end is connected at 75, in a detachable manner, to the upper end of the buoy. An intermediate fastening hook 76 may be provided for the cable 73 near the lower end of the board.

Now as the sinking ship descends from the floating buoy it will be noted that the ship is not only connected with the buoy 15 through the hose 26, for signaling and communicating purposes, but that also said buoy is connected to the rescuing container by line 73. Now after a buoy has been located by the rescuing party and after telephonic communication has been established 20 with the victims of ship wreck in safety chamber 8, line 73 will be detached from the buoy and will be threaded through a bore 77 of a grapple head 78. Grapple head 78 is provided with a connecting portion 79 for attachment to a hoisting cable 80, with which the rescuing vessel will be provided. Hoisting cable 80 is shown trained about a windlass 81 on the rescuing vessel 4. The 25 grapple is provided with grapple hooks 82 which are hinged at 83 to the grapple head 78 and which are held in predetermined spaced relation by lugs 84 so that the grapple hooks will take over and engage flange 30 71 as shown in Fig. 6. Thus after the grapple head has been threaded onto line 73 it will descend thereon and be guided thereby into coupling relation with grapple head 70 thereby establishing hoisting connection between 35 the rescuing vessel and the rescuing elevating container 66 so that the occupants of the latter can be elevated from the sunken ship to the water surface and taken on board the rescuing vessel.

40 Means is provided for withdrawing or lowering the container into compartment 9 for the purpose of rendering the container accessible for rescue of another of the occupants of safety chamber 8. As illustrated, a lowering cable 85 is connected with a container at 86 and is trained about a windlass 87 which is mounted or journaled at 88 in the bottom of compartment 9. A crank 89 extends through partition 7, by means of a 45 suitable packing gland 90 so that the windlass 87 may be operated from safety chamber 8. I desire to make the container 66 of rounder formation near its lower end, as indicated at 91 so that it will readily be drawn through opening 65. Access to the safety chamber 8 is gained through a man hole 92 which is provided with a cover or closure 93 which is hinged to the housing 6 at 94. A hook 95, mounted at 96, may be 50 applied to an eye 97 to hold the door or

cover 93 in an open position, as shown in dotted lines in Fig. 3. A bolt 98 is connected with said door and a hand wheel 99 serves to maintain said door in a tightly closed position in a manner similar to the 70 construction shown in Fig. 7. It will now be seen how access is gained to the safety compartment 8 and thence to the container chamber 9 and it will also be noted that the two chambers are normally maintained in 75 air tight sub-division with respect to each other.

Reference will now be made to the construction of the rescue container 66 to illustrate the manner in which an occupant may 80 enter and close the same.

The bottom of said container 66 is provided with an opening 100 which is closed by a lower head 101 having threaded engagement with said opening. Said head 85 101 is provided with a hand wheel rim 102 whereby it may be opened from the exterior of said container 66 by a person located in compartment 9. Said head is also provided with a rigidly mounted interiorly projecting 90 hand wheel 103 by means of which the head 101 may be closed or opened by an occupant in container 66. It will be understood, that the occupant upon entering container 66 may remove the head 101 by grasping hand 95 rim 102 and that after the occupant has entered the container 66 one of the other victims may close the head 101. However, when the last of the victims enters the container 66 he will close the same by means of 100 hand wheel 103. Interiorly the container 66 is provided with a foot rest flange 104 on which the occupant may stand after entering the container. The container may be suitably upholstered, as indicated at 105 and 103 a saddle 106 may be provided, together with the hanger strap 107, for convenience of the occupant. It will be understood that while the container is substantially air tight the occupant will not be compelled to remain 110 therein for a sufficient length of time to cause distress due to lack of oxygen.

Occasion may require an immediate supply of air such as the pump 18 could not instantly supply and therefore I equip the 115 safety chamber 8 with a plurality of air tanks 108, filled with compressed air under high pressure and supported in any desirable manner by means such as a strap bracket 109. Pipes 110 lead from the tanks 120 108 to a manifold 111 and each pipe 110 has interposed therein a controlling valve 112. A valve 113 is provided for sudden admission of air to safety chamber 8 in cases where even reversal or normal action of pump 18 125 does not afford the required supply or in case of impairment of the apparatus effecting operation thereof. Manifold 111 projects into compartment 9, as indicated at 114 and the air supply to compartment 9 is 120

regulated by valve 115. Air moves plus 116 from chamber 8 into the exterior of the housing and egress through said pipe 116 controlled by a valve 117 whose valve stem 8118 is set so as to plug a portion of said pipe 116 in this position so that the first valve 117 will be closed and the valve 116 will be open.

After the last occupant enters chamber 8 and says "I am ready to be rescued" the air tank 119 will close back into said chamber and be relieved by a telephone signal which will then descend to the sea for elevation of said chamber 8. As the container leaves compartment 9 many of the latter will be open to ingress of water because it would be impossible to maintain pressure in chamber 8 when the latter is open since such air would simply ascend through the water to the surface of the sea. After the elevated container 63 has been relieved of its occupant and has been again closed, telephone signal will be sent to safety chamber 8 and the windlass 87 will be operated to lower the container 9 into the position shown in Fig. 2. As the container enters the compartment 9 it will take out a portion of the water therein. After the container 63 has been firmly seated in the position shown to close compartment 9 then egress pipe 118 will be opened and valve 115 will be opened to discharge air into compartment 9 and force the water out of said compartment. Holes as indicated at 120, may serve to indicate when the water has been expelled from chamber 9. Then the door 11 may be opened for passage of another occupant of chamber 8 into container 63. One by one the occupants will be transferred until the last remaining occupant enters the container. After such last occupant has been rescued, the final closure of container 63 to chamber 9 will be immaterial as the main purpose is to effect rescue of all 45 of the occupants.

It will be seen that my invention distinguishes from a submarine by reason of the fact that my invention includes a ship which is provided with a housing which is habitable irrespective of independent of the ship. In other words the ship may be injured and sunk but the housing will be habitable to save the victims from drowning.

It is believed that the advantages and utility of my invention will now be fully understood and appreciated and while I have herein shown and described one specific form of my invention, I do not wish to be limited thereto except for such limitations as the claims may require.

I claim:

1. In a marine life saving apparatus, a ship, an air tight habitable housing mounted on said ship, a buoy having an air tight take and being free to remain on the surface

or the sea, shafts and a hollow air supply pipe connected with said buoy and entering the interior of said housing, substantially as described.

2. In a marine life saving apparatus, a ship, an air tight habitable housing mounted on said ship, a buoy having an air tight take and being free to remain on the surface, as the ship 75 comes into a harbor and supplying conduit means connected with a hose and having one end connected with the interior of said housing, substantially as described. 86

3. In a marine life saving apparatus, a ship, an air tight habitable housing mounted on said ship, a human rescue container projecting into and having an air tight fit in said housing and provided with a grapple head projecting from said housing, a captive line connected with said container, means connected with said captive line and operable in said housing for lowering said container into said housing, a buoy, a guide line detachably connected with said buoy and connected with the grapple head of said container, and a hoisting cable having a grapple provided with means for making connection with said guiding line 95 to guide said grapple into hoisting connection with said grapple head of said container, substantially as described.

4. In a marine life saving apparatus, a ship, an air tight habitable housing mounted on said ship, a human rescue container projecting into and having an air tight fit in said housing and projecting from said housing, a captive line connected with said container, means connected with said captive line and operable in said housing for lowering said container into said housing, a buoy, and a line connected with said container and with said buoy, substantially as described. 100

5. A human container for life saving apparatus of the character described comprising in combination, a hollow body proportioned to receive a human being and provided with a lower end entrance opening 115 and a foot rest flange adjacent said opening, a closure for said opening having a hand grip for operation by a person outside of said hollow body and also provided with a hand grip projecting into and adapted for 120 operation by the occupant of said body, substantially as described.

6. In a marine life saving apparatus, a ship provided with an air tight airtight housing, means containing means, means operable on the outside of said ship and means operable at the end of said housing for successively raising and lowering said containing means 125 in and out of said housing in the surface and vice versa for successive transfer of the contents 130

pants from the sunken ship to the surface, substantially as described.

7. In a marine life saving apparatus, a ship provided with a water tight habitable housing, a buoy carried by said ship and being free to remain at the surface of the water after the ship sinks, a human container movable into said housing, a line connected with said container and said buoy, 10 and hoisting means at the surface coacting with said line for operative connection to hoist said container to the surface, substantially as described.

8. In a marine life saving apparatus, a ship provided with a water tight habitable housing, a human rescue container project-

ing into said housing, and having a grapple head, a buoy carried by said ship and being free to remain at the surface as the ship sinks, a guiding line connected with 20 said container and buoy, and automatically acting hoisting grapple means at the surface for coaction with said guiding line to establish hoisting connection with said grapple head, substantially as described. 25

In testimony whereof I affix my signature in presence of two witnesses.

JOSEF KONRAD.

Witnesses:

H. E. SMITH,
EDNA BROYLES.
